WINDOW CONSTRUCTION

Robert S. Blair, New York, N. Y.

Application March 29, 1935, Serial No. 13,622

5 Claims. (Cl. 292—76)

This invention relates to devices for use in connection with window sashes and more particularly to sash-holding devices.

One of the objects of this invention is to provide a device of the above character which will be simple, practical and thoroughly durable. Another object is to provide a device of the above character which may be easily installed by unskilled labor. Another object is to provide a practical device of the above character which will prevent rattling of the sash in the frame while still permitting the sash to be easily moved. Another object is to provide a device of the above character which will form an effective weather strip to prevent the atmosphere entering around the edges of the sash. Other objects are to provide devices of the above character of simple and inexpensive construction and efficient and dependable action. Other objects will be in part obvious and in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings in which are shown several of the various possible embodiments of my invention,

Figure 1 is an elevational view of a window with certain of the parts broken away having the device installed therein;

Figure 2 is a perspective view of a part of a window having the device installed therein;

Figure 3 is a sectional view taken along line 3—3 of Figure 1;

Figures 4 and 5 are sectional views similar to Figure 3 having modifications of my device installed therein;

Figure 6 is a plan view of the modification in Figure 5 with certain of the parts broken away;

Figure 7 is a perspective view of a modification of my device; and

Figure 8 is a side plan view of the modification in Figure 6.

Similar reference characters refer to similar parts throughout the several views of the drawings.

As conducive to a clearer understanding of certain features of this invention, it might here be pointed out that previous methods for holding a member at any desired position upon a track within a frame have been accompanied by excessive cost and ineffectiveness of result. Many of these devices use weights to counterbalance the

weight of the member and, of necessity, are cumbersome. Furthermore, the counterbalances must be positioned in a place which is not easily accessible and where it would not be easy for the ordinary layman to repair. Furthermore, the installation of counterbalances usually requires the services of skilled labor adding to the cost of performing the job. When one of these systems has been installed, it usually performs only this one function of forming a means for adjusting the position of a member within a frame and neither prevents rattling, which is usually found in all such systems, nor does it serve as a weather stripping in such a case as when a sash is mounted in a window frame. Among the several objects of this invention are to provide devices and methods for overcoming the above-mentioned difficulties.

Referring now to the drawings in detail, there is shown in Figure 1 a window frame generally indicated at 10 which is preferably constructed of wood or the like although a metal frame may be used. Window frame 10 may be constructed in the usual manner having a pair of stiles 11, a top portion 12, and a sill 13 all of which are secured together by any suitable means such as by screws or nails.

Preferably near the center of stiles 11 and secured thereto I have placed guide strips 14. Guide strips 14 preferably extend from the top portion 12 to the sill 13 and have their sides 15 and 17 (Figure 3) perpendicular to the stiles 11. Secured to the outer edges 15 of the stiles 11 and extending inwardly toward the center of the frame 10 beyond the inner surface 20 of the stile 11 are cover boards 18. The sides 19 (Figure 3) of the cover boards 18 are preferably parallel to the sides 16 of the guide strips 14 and thus guide strips 14, stiles 11 and cover boards 18 form tracks on opposite sides of the frame 10 within which sash 21 may slide, its movement in one direction being limited by the top portion 12 and in the opposite direction by the sill 13.

Between the sides 22 of the sash 21 and the surface 20 of the stiles 11 there is a space 23 (Figure 3) which extends for the length of the side 22 of the sash 21 and is rectangular in cross section. The width of this rectangle preferably is a great deal smaller than the length which is the width of the stile 11 between the side 16 of the guide strip 14 and the side 19 of the cover board 18 such as is usually found in constructions of this type.

Within this space 23 and preferably extending longitudinally between the top portion 12 and the

sill 13 and in the track within which the sash 21 slides, I place a resilient strip 24 preferably constructed of metal such as stainless steel. Preferably this strip is concave in cross section having its convex side toward the side 22 of the sash 21 and between its two edges 25 and 26 having less length in cross section than the space between the guide strip 17 and the cover board 18. Preferably the width in cross section of this strip when positioned upon the stile 11 is sufficiently greater than the width of the cross section of the space 23 so that the strip 24 will be compressed by the sash side 22 against the stile 11 and exert a resilient force against the 16 side of the sash.

Preferably, the inner edge 25 of strip 24 is turned upwardly away from the stile to form a lip 27. This prevents friction between this edge of the strip and the stile when the strip is compressed by the side 22. The opposite edge 26 of the strip 24 is preferably secured to the stile by any suitable means, as by a wedge shaped nail 28. If this type of nail is used and the strip is not punched for the nails, the edges 17 immediately surrounding the nail as it is driven through the metal will be bent inwardly (Figure 3) and into the stile forming a very secure connection. These nails 28 would be driven through the strip 24 at suitable intervals (Figure 2) to hold the edge of the strip securely against the stile. Thus, I have provided a resilient strip preferably concave and constructed of resilient sheet metal capable of being attached to the stile 11 of a window frame and lying in the track in which the sash 21 slides. Also this strip 24 is sufficiently concave as to be compressed by the side of the sash 21 when it is in position thus exerting a resilient force against the side 22 of sash 21 holding the sash in any desired position upon the tracks in the frame.

Immediately below the edge of sides 22 the compressing force exerted by the sash 21 upon the resilient strip will be released and the strip will resiliently stand out forming stops 29. These stops 29 will always be immediately below the lower edges of the sides 22 wherever the sash 21 may be placed within the frame 10 and therefore will form a second means for holding the window in any desired position within the frame.

The strips 24 which I have thus placed between the sides of the sash 21 and the stile 11 also form a very effective weather stripping. As the strip is attached to the stile 11, a tight connection will be formed between the two, and when the strip 24 is compressed by the sash 21 the strip will exert a constant resilient force both against the stile 11 and the side of the sash 22, effectively sealing this aperture which ordinarily exists between the sides of the usual sash and stile construction. Also because of the constant resilient force exerted by the resilient strip against the side 22 of the sash, the sash will be prevented from rattling or vibration as the resilient force will counteract any movement of the sash caused by the wind or vibration.

Thus, this resilient strip 24 which is preferably concave but may take any other desirable shape not only serves as an effective stop for the sash but also serves both as weather stripping and as an anti-rattler.

Referring now to Figure 4, one of the many possible modifications of the strip 24 is shown attached to stile 11 and exerting pressure against the side 22 of the sash 21 which is compressing it. This type preferably consists of two parts 30

and 31 concave in cross section connected by a convex portion 32 all of these surfaces preferably being pressed from one resilient metal strip. This forms two surfaces pressing against the side 22 of the sash 21 and leaves a portion 32 5 which may be securely attached to the stile by nails 28 or by any other suitable means.

A second modification is shown in cross section in Figure 5 a channel 33 having been cut into the edge 22 of the sash 21 and a concave metal strip 24 having an upturned lip 27 is secured in this channel so that the concave surface of the strip 24 faces the sash and the convex surface abuts against and is compressed by the stile 11 when the sash is in position against the 15 stile. To prevent the upper and lower edges 39 of the concave strip 24 from digging into or forming undue friction with the stile 11 as the sash 21 slides in its track, I preferably secure the ends of the strip to the ends or sides of the 20 stile. In Figure 6, I have shown the edges 39 of the strip 24 secured to the side of the sash at 40 and secured to the end of the sash at 41. The edges are secured by any suitable means such as by nails 42.

Referring now to Figure 7, I have shown a series of cut-out portions 34 in the side 26 of the strip which is to be secured to the surface on which the strip is to rest. These cut-out portions, which are preferably in the shape of triangles, are cut through strip 24 only on two edges 35 and 36 and then bent downwardly using the third edge 37 as an axis to form a series of pointed lugs 38 (Figure 8) preferably perpendicular to the plane drawn between the edges 26 35 and 27 of the concave strip 24. These lugs will form an efficient means for attaching the strip 24 to any surface. Thus, I have provided two modifications for placing and shaping the strip each of which will perform the unique function 40 of acting as a stop for a sash in a window frame, an effective weather strip, and an anti-rattler. And I have also provided an efficient and inexpensive means for attaching the strip to a surface.

It will now become clear that with my unique and simple device and method, I am able to perform three definite functions in holding a sliding member at any desired position within its track, sealing the aperture between the sliding member and its track, and preventing excessive lateral movement of the member as would cause rattling of the member within its tracks. It is to be understood that each of these functions is of independent value and the construction may be arranged to accomplish any one or more of them as an embodiment of features of the invention. Furthermore, it will be noted that this has been accomplished in a simple and efficient manner by a device which may be manufactured at extremely low cost. All of the factors accomplished by this device offer material advantages in the production of this device and to the user.

It will thus be seen that I have provided a thoroughly practical device for holding a sliding member within its frame at any desired position in which the several objects hereinabove mentioned as well as many others are successfully accomplished.

As many possible embodiments may be made of the above invention and as many changes might be made in the embodiment above set forth, it is to be understood that all matter hereinbefore set forth, or shown in the accompany-

ing drawings, is to be interpreted as illustrative and not in a limiting sense.

I claim:

1. In a construction of the nature described, comprising a sash member and a stile member along which said sash slides, in combination, a transversely resilient metallic strip interposed between said members and shaped to be yieldingly compressed thereby, and securing devices extending along said strip to hold the same against one of said members, said devices having tapering head portions contacting and holding portions of the strip into the member which they enter, whereby said strip may be substantially flattened against the member to which it is secured.
2. In a construction of the nature described, comprising a sash and a window frame in which said sash slides, in combination, a transversely resilient strip interposed between said sash and frame and secured to said sash, said strip having a yielding portion spaced from the sash and pressing against the frame substantially throughout the length of the sash with the end edges of the strip toward the top and bottom of the sash inclined toward the sash to permit the strip to slide freely along the frame.
3. In a device of the nature described, for use in a window frame and sliding sash construction, in combination, a resilient metallic strip curved transversely interposed between said sash and said frame and extending at least throughout substantially the length of the sash said curved portion containing said sash, said strip being flattened under pressure between the surface of

said sash and said frame and springing outwardly to its normal form beneath the lower edge of the sash to support the sash in any position to which it is moved.

4. In a device of the nature described, for use in a window frame and sliding sash construction, in combination, a resilient metallic strip curved transversely interposed between said sash and said frame and extending at least throughout substantially the length of the sash, said curved portion contacting said sash, said strip being flattened under pressure between the surface of said sash and said frame and springing outwardly to its normal form beneath the lower edge of the sash to support the sash in any position to which it is moved and means for fastening one edge of said strip to said frame with its transversely curved part contacting the sash whereby the space between said frame and said sash is tightly closed and lateral vibration of the window is prevented.

5. In a construction of the nature described comprising a sash and a window frame in which said sash slides, in combination, a transversely curved resilient strip interposed between the side member of said sash and the frame member and secured to one of said members, said strip having a yielding portion spaced from said last-mentioned member and pressing against the other of said members substantially throughout the length of the sash with the end edge of the strip inclined longitudinally toward the member to which it is secured to permit the sash to slide freely along the frame.

ROBERT S. BLAIR. 35
